J. DELPECH

APPARATUS FOR THE MANUFACTURE OF ARTIFICIAL FILAMENTS

Filed Dec. 7, 1925

UNITED STATES PATENT OFFICE.

JACQUES DELPECH, OF RENNES, FRANCE.

APPARATUS FOR THE MANUFACTURE OF ARTIFICIAL FILAMENTS.

Application filed December 7, 1925. Serial No. 73,907.

Artificial silk fibers which are obtained from solutions of cellulose, such as cellulose acetate or nitrocellulose, are produced in the form of filaments which have very irregular cross sections. The present invention has for an object the provision of a process and apparatus for spinning which forms the filaments obtained in a uniform flat shape with the general appearance of thin microscopic 10 ribbons.

This process may be carried out by various different forms of apparatus, certain of which are illustrated in the accompanying drawings in which

15 Figure 1 is a vertical cross section of a metier casing of the usual type, having one form of the invention embodied therein.

Figure 2 is a cross section through the spinneret and tube supplying the spinning 20 solution, showing a modification.

Figure 3 is a diagrammatic illustration of a further modification.

Figure 4 is a side view partly in section of a still further modification applied to a spinneret 25 which produces a single filament.

Figure 5 is a similar view of a spinneret, which produces a number of filaments.

Figure 6 shows in cross section the usual 30 filaments produced.

Figure 7 shows in similar cross section filaments produced by the process of this invention.

There is shown the usual main casing A in which are tubes 1 through which the spinning 35 solution is supplied and connected to these tubes are the spinnerets 2. In the usual practice these spinnerets are located so that the longitudinal axis thereof lies in the same line as the direction taken by the thread issuing from said spinneret. This thread 40 3 passes about suitable guides 4 and is wound on rollers 5. Where the thread is drawn in a direction which constitutes an extension of the axis of the spinneret, it is apt to be irregular 45 in cross section and may assume forms such as illustrated in Figure 6.

The spinnerets 2 in the form of the invention illustrated in Figure 1, are placed at an angle to the direction of travel of the thread 50 so that the line of travel of the thread from the spinneret to the guides is very nearly at right angles with the axis of the spinneret. The exact angle may be varied without departing from the invention, but it should be

preferably quite a large angle. In this way 55 the thread is flattened and becomes substantially uniform in cross section as is indicated in Figure 7.

This change of direction of the thread by which this flattened filament is formed, may 60 be attained in various ways. In Figure 2 there is a modification in which the spinneret 2 which is formed of glass preferably has its extreme end 6 bent at an angle to the axis of the body thereof and the thread 3 is drawn 65 off in a line substantially parallel to the axis of the body of the spinneret, which is of course at quite an angle to the tip portion 6. In this case the spinneret itself is attached to the supply tubes 1 in the usual form. 70

In the form of the invention illustrated in Figure 3, the tube 2 is attached to the supply tube 1 at an angle as shown in Figure 1 and is also provided with the bent tip 6, as shown in Figure 2. A change of direction may be 75 easily made somewhat greater in this form of the invention than in the other.

In the form shown in Figure 4, the usual form of spinneret 2 is employed and it is attached to the tube 1 in the usual manner. 80 However, the guide 8 is located at a short distance from the tip of the spinneret and at one side so that the thread when led around this guide is drawn at quite an angle to the axis of the spinneret, thus attaining the same 85 result as attained by the other modifications. Figure 5 shows this same form of the invention but applied to a spinneret which produces a plurality of filaments at one time, all of which are led around a common guide 90 8 located at one side of the spinneret.

It is obvious that the essence of the invention consists in leading the thread away from the tip of the spinneret at a sharp angle to the axis of the body of the spinneret so as 95 to flatten the resulting filament by drawing it across the edge of the spinning orifice. It has been found that the original filaments are given a more uniform shape in this manner and that the flat shape imparted thereto permits them to be spun into fabrics with greater advantage than is the case with the usual irregular filaments. 100

It is obvious that the process may be applied to artificial silk which is spun from any desired solution and that the form of apparatus employed may be varied widely without departing from the invention as set forth 105

in the process. The invention is, therefore, to be regarded as limited only by the scope of the appended claim.

I claim:

5 A device for spinning filaments from cellulose solutions comprising a spinneret having its delivery end bent at an angle to the axis

of the body thereof and a guide for said filament located in a line substantially parallel to the said axis, so that the filament is caused to change its direction of movement as it issues from said orifice. 10

In testimony whereof I affix my signature.
JACQUES DELPECH.
